US00D804354S

(12) **United States Design Patent** (10) **Patent No.:** **US D804,354 S**
Strub (45) **Date of Patent:** **** Dec. 5, 2017**

(54) **CAR**

(71) Applicant: **Alex Strub**, Frasnacht (CH)

(72) Inventor: **Alex Strub**, Frasnacht (CH)

(**) Term: **15 Years**

(21) Appl. No.: **35/501,499**

(22) Filed: **Mar. 9, 2016**

(80) **Hague Agreement Data**

Int. Filing Date: **Mar. 9, 2016**

Int. Reg. No.: **DM/090032**

Int. Reg. Date: **Mar. 9, 2016**

Int. Reg. Pub. Date: **Sep. 9, 2016**

(51) **LOC (10) Cl.** **12-08**

(52) **U.S. Cl.**

USPC **D12/86**

(58) **Field of Classification Search**

USPC D12/82, 86, 88, 90-92, 93; D21/421,
D21/433-434

CPC B62D 35/00; B62D 25/00; B62D 25/06;
B62D 33/00

See application file for complete search history.
